UNITED STATES PATENT OFFICE

ALBERT F. DORMEYER, OF CHICAGO, ILLINOIS

MUFFLER

Application filed March 19, 1928. Serial No. 262,918.

This invention pertains to mufflers for silencing or blending the staccato reports of the explosion exhaust of internal combustion engines and the like, and while particularly adapted for internal combustion engines of the explosion type, may be used in connection with other types of power plants. The invention disclosed herein is an improvement upon that described and claimed in my copending application Serial No. 117,294, filed June 21, 1926, entitled "Mufflers."

One of the primary objects of the present invention is to provide a more efficient, simple and economical construction than that described in my said copending application.

Another important object is to provide a novel type of baffle element and a novel type of baffle element arrangement whereby the gases of each explosion are broken up into different streams and in part retarded, then rebroken into different streams and in part retarded, and so on, during their passage through the muffler, and whereby the gases of each explosion will be caused to travel successively at high velocity and low pressure and at low velocity and high pressure through the baffles and expansion chambers, respectively, without appreciable back pressure, so that when the gases issue from the opposite end to the muffler it will be in a substantially steady stream with a subdued hissing sound.

A further object is to provide a novel muffler construction in which the baffle elements, when combined in their proper relationships within the muffler casing, serve to partition the casing longitudinally and transversely into a number of chambers and in which the baffle elements, due to their construction, are substantially self-supporting.

Still further objects, advantages, functions and uses of the invention will be or should become readily appreciated after reading the following description and claims and after viewing the drawing in which,

Fig. 1 is a longitudinal view of one form of muffler constructed in accordance with the invention, a portion being broken away to show the baffles,

Fig. 2 is a similar view of the same muffler

construction taken substantially along the center line of Fig. 1, and

Fig. 3 is a transverse sectional view taken along the line 3—3 of Fig. 2 looking in the direction of the arrows.

The muffler illustrated is preferably made of sheet metal and includes what may be termed upper and lower semi-cylindrical casing sections 2 and 3 and a plurality of baffle elements, generally designated 4, which are suitably secured by and between the casing sections 2 and 3 after the manner fully described in my copending application, but which will be briefly described herein.

Each casing section is provided with spaced transversely extending corrugations 5 which not only serve to strengthen the sheet metal, but also provide internal grooves or recesses into which the semi-circular edges of the baffle portions of the baffle elements extend and are received and secured, as will be understood. The sections 2 and 3 may be secured together in any manner, but I prefer to provide each with flanges 6 along its longitudinal edges so that the parts of the casing may be welded, riveted or bolted together and so that marginal portions 7 of the baffle elements 4 may be rigidly clamped between the flanges. This produces a very simple, yet strong, rigid, and effective structure.

Each element 4 is made from sheet metal and while in some respects alternate elements differ slightly from one another, as will be pointed out, they are all substantially of Z-shape having a longitudinally extending web portion 8 and two legs or baffle portions 9 and 10, struck up substantially at right angles to the web 8 and extending in opposite directions.

The marginal edges 7 are, of course, in the present construction, formed on the web portions 8, while the grooves 5 receive the free end edges of the baffle portions 9 and 10, which at these edges are made semi-circular for the purpose. The spacing of the webs 8 is such that while the leg or portion 9 is received in one corrugation 5 in one section of the casing, the opposite leg or portion 10 is received in the next succeeding corrugation in the other half of the casing, and succeed-

ing elements abut one another, as shown at 11, to provide a substantial continuity of the longitudinal web or partition and a strengthening of the assembly.

5 From the foregoing, it will be observed that the construction provides a plurality of what I shall term expansion chambers on each side of the longitudinal partition or web formed by the web portions 8. Each web and 10 leg portion 8, 9 and 10 is provided with a plurality of openings at the end of a tapered passage, tapered in the direction of gas flow. These apertures or openings through the baffles are of different size in the leg portions 9 15 and 10, although they may be of the same size throughout all of the web portions 8. For instance, viewing the left hand end of Fig. 2, the apertures or openings 12 are smaller than the apertures or openings 13 which 20 are, in the embodiment illustrated, of the same size as the apertures 14. In the next succeeding baffle the apertures or openings 15 are all of the same size, whereas in the next succeeding baffle the apertures 16 and the 25 leg portions 9 and 10 are of the same size, but smaller than the apertures 17 in the web 8 thereof. This arrangement is continued throughout for all of the baffle elements, every other baffle element having all of its 30 apertures of the same size and intermediate elements having the apertures or openings through the leg portions of smaller size than the apertures or openings through the web 35 portions and smaller than the apertures through the preceding and succeeding baffle elements.

Thus the gases from an explosion, when they enter the left hand end of the muffler illustrated, are divided and a larger proportion 40 pass through the apertures 13 and 14 than through the apertures 12 of the first baffle element. The gases which have passed into the first lower chamber pass into the second lower chamber where their direct passage, on through the muffler, is retarded by 45 the small apertures 16 of the next succeeding baffle element. Therefore, a large proportion of the gases are forced upwardly into the chamber thereabove and there mingle with 50 some of the gases which have passed through the small apertures 12. This division and retarding and intermingling of the gases continues through the remaining elements and chambers until the right hand end of the 55 muffler is reached where they pass out in a substantially continuous uninterrupted stream. As the gases pass through the orifices or openings in the baffles their pressures are reduced and their velocities increased, 60 due to the Venturi construction of the walls of the openings, but when they enter the succeeding chamber they expand, their velocity is reduced and their pressure increased. This 65 action aids in breaking up and intermingling

or blending the gases and is particularly effective for its purposes.

It is believed that the functions, advantages and uses of the particular embodiment of the invention illustrated and described will be appreciated from the foregoing. However, since various modifications and arrangements may be made in the construction illustrated and described, I do not desire to be limited thereto, but only by the spirit of 75 the invention and the scope of the appended claims.

I claim:

1. A muffler comprising a longitudinal casing, a plurality of structurally independent baffle elements, each substantially of Z-shape in side elevation, so disposed in said casing as to provide a substantially continuous longitudinal web portion and transverse baffle portions extending from each side of the web portion to the casing, and means securing said elements in their relative positions in 80 said casing.

2. A muffler comprising a longitudinal casing, and a plurality of structurally independent baffle elements disposed in series within 85 said casing, each element having a longitudinally extending portion and oppositely directed transverse portions integral with the first said portion and extending from opposite ends thereof to the interior wall of the 90 casing.

3. A muffler comprising a substantially cylindrical casing, a plurality of structurally independent sheet metal elements disposed in 95 said casing, each element being substantially Z-shaped with the webs of the Z's directed longitudinally of the casing and substantially contiguous with one another and with the top and bottom portions of the Z's directed transversely of the casing, and means securing said elements in their relative positions in 100 said casing.

4. A muffler comprising a substantially cylindrical casing and a plurality of sheet metal baffle elements disposed in said casing, each element having a portion extending longitudinally and transversely of the casing and two end portions bent substantially at right angles to the first said portions in opposite 110 directions and extending transversely of the casing, all of the elements being disposed in the casing with the first said portions of each in substantial alignment and so as to provide a substantially continuous partition 115 longitudinally of the casing.

5. A muffler comprising a sheet metal casing, a plurality of Z-shaped transverse sheet metal baffles therein, said baffles each having a plurality of hollow conical projections truncated at their apices to provide an opening through each, the walls about and defining the openings in the baffles converging in the direction of the line of flow of gases 120 through the muffler.

6. A muffler comprising a casing and a plurality of transverse, spaced sheet metal baffles of Z-shape therein, adjacent baffles defining a gas receiving chamber between them, each baffle upstream relative to the direction of gas flow having a plurality of hollow conical projections truncated at their apices to provide an opening through each, said projections projecting into said chamber; the surrounding walls of each opening converging in the direction of gas flow.

7. A muffler comprising a longitudinal casing, a plurality of structurally independent baffle elements, each substantially of Z-shape in side elevation, so disposed in said casing as to provide a substantially continuous longitudinal web portion and transverse baffle portions extending from each side of the web portion to the casing, and means securing said elements in their relative positions in said casing, each transverse baffle portion and said web portion having a plurality of apertures therethrough.

8. A muffler comprising a longitudinal casing, a plurality of structurally independent baffle elements, each substantially of Z-shape in side elevation, so disposed in said casing as to provide a substantially continuous longitudinal web portion and transverse baffle portions extending from each side of the web portion to the casing, and means securing said elements in their relative positions in said casing, each transverse baffle portion and said web portion having a plurality of gas passages therethrough, said passages having walls converging in the direction of gas flow.

9. A muffler comprising a longitudinal casing, and a plurality of structurally independent baffle elements disposed in series within said casing, each element having a longitudinally extending portion and oppositely directed transverse portions integral with the first said portion and extending from opposite ends thereof to the interior wall of the casing, each transverse portion having a plurality of openings therethrough, said openings having walls converging in the normal direction of gas flow.

10. A muffler comprising a longitudinal casing, and a plurality of structurally independent baffle elements disposed in series within said casing, each element having a longitudinally extending portion and oppositely directed transverse portions integral with the first said portion and extending from opposite ends thereof to the interior wall of the casing, each transverse portion and each longitudinally extending portion having a plurality of openings therethrough, the openings in each transverse portion having walls converging in the normal direction of gas flow.

11. A muffler comprising a longitudinal casing, and a plurality of structurally independent baffle elements disposed in series

within said casing, each element having a longitudinally extending portion and oppositely directed transverse portions integral with the first said portion and extending from opposite ends thereof to the interior wall of the casing, each transverse portion and each longitudinally extending portion having a plurality of openings therethrough, the openings in each transverse portion having walls converging in the normal direction of gas flow.

12. A muffler comprising a longitudinal casing and a plurality of metal baffle elements disposed in said casing, each element having a portion extending longitudinally and transversely of the casing and a portion at each end of the first said portion extending at an angle thereto transversely of the casing, said last mentioned portions extending in opposite directions, said elements being disposed in said casing with the first said portions in substantial alignment and abutting one another, alternate similarly extending second said portions of a group of said elements having apertures of one size therethrough, and intermediate similarly extending second said portions of said elements of the same group having apertures of a different size therethrough.

In witness of the foregoing I affix my signature.
